(57) CLAIM

The ornamental design for a storage container, as shown and described.

DESCRIPTION

FIG. 1 is a front view of a storage container showing the claimed design;

FIG. 2 is a rear view thereof;

FIG. 3 is a left view thereof;

FIG. 4 is a right view thereof;

FIG. 5 is a top view thereof;

FIG. 6 is a bottom view thereof; and,

FIG. 7 is a top perspective view thereof.

The broken lines in the figures illustrate portions of the storage container that form no part of the claimed design. The shade lines in the figures show contour and not surface ornamentation.
